ABSTRACT OF THE DISCLOSURE

A device for straightening circular cross section workpieces having diameters which vary along their length, comprising a set of straightening rollers and a set of driving rollers engaging the periphery of each workpiece with the straightening rollers being disposed at approximately opposite sides of the workpiece. Means are provided to drive the driving rollers to rotate, axially translate, and straighten the workpiece, along with means to move at least one of the straightening rollers to and from the other straightening rollers in response to variations in the diameter of the workpiece.

The present application is a continuation-in-part of application Ser. No. 440,886 filed Mar. 18, 1965, and now abandoned.

BACKGROUND OF THE INVENTION**Field of the invention**

The present invention relates to a device for straightening circular cross section workpieces of varying diameters along their lengths.

Prior art

Roller type devices are generally known for straightening cylindrical workpieces, usually in the form of bars and tubes. These known devices usually impart a combined rotary and translatory motion, i.e. a helicoidal motion to the workpiece, through the combined action of a plurality of driving and idle rollers, the axes of which are suitably inclined with respect to the axis of each workpiece to be straightened.

The assembly of rollers, besides impressing a continuous helicoidal motion to the workpiece due to their relative position with respect to the workpiece (which is usually opposed, alternated, staggered, etc.) also effects a continuous deflection or bending of the workpiece in all directions, and as the workpiece goes forward, this deflection extends throughout the length of the workpiece and overcomes its yield strength to straighten same.

In these known straightening machines, a suitable inclination of the driving and idle roller axes relative to the axis of the workpiece is performed as a function of the outer diameter of the latter. Depending on the deformation or bending rate to be eliminated, and on the thickness and physical characteristics of the workpiece, suitable thrusts or pressures are impressed on said bar through rollers which are able to provoke the required deflections in all directions and throughout the length of the workpiece.

In the conventional straightening machines, the rollers, after having been positioned in the correct position, are locked and retained in this position until all workpieces of the same stock are straightened. When other workpieces of a different diameter are to be straightened, the working position of the rollers must be adjusted when the

2

machine is not in operation. Therefore, for each position of the rollers, they can only straighten cylindrical workpieces having the same diameter throughout their length.

SUMMARY OF THE INVENTION

It is therefore an object of the present invention to provide a roller straightening device adapted to straighten workpieces having a circular cross section throughout their length, but having diameters which increase or decrease in any range. These workpieces may be hollow or solid, may be frusto conical in shape, or partially frusto conical and partially cylindrical, etc. Furthermore, they may be in the form of tapered poles formed by several members of an increasing or decreasing diameter.

10 The straightening rollers of the present invention are mounted in means which are of the irreversible type, i.e. adapted to maintain a fixed position regardless of the load impressed upon them and to controllably move in response to variation in diameter of the bar.

15 Briefly summarized, the device of the present invention is characterized by the use of a set of straightening rollers and a set of driving rollers which are suitably arranged with their axes inclined relative to the axis of the workpiece to be straightened. The driving rollers 20 rotate the workpiece and impart an axial movement thereto by cooperating with the periphery of the workpiece, and at least a portion of the straightening rollers are adapted to move relative to the axis of the workpiece during the movement of the latter in response to variation in diameter of the bar.

BRIEF DESCRIPTION OF THE DRAWINGS

The invention will now be disclosed in the following description by making reference to the accompanying drawings in which:

25 FIG. 1 is an elevational view of the device according to the invention;

FIG. 1A is a bottom view of the device showing the relative positioning of the rollers;

30 FIGS. 2 and 3 are elevational views, partially in section, of two different mechanical driving systems; and

FIG. 4 is an elevational view, partially in section, of a device for varying the inclination of the axis of the roller with respect to the axis of the workpiece.

DESCRIPTION OF THE PREFERRED EMBODIMENTS

Referring specifically to FIG. 1 of the drawings, a pair of rollers A₁ and A₂ are disposed on one side of a workpiece H having an axis W—W, and three rollers B₁, B₂, and B₃ are disposed on the opposite side of the workpiece, it being understood that the number of these rollers may vary as necessary. Rollers B₁, B₂, and B₃ are rotatably mounted in forks C₁, C₂, and C₃ for rotation about their axes Z₁ to Z₃, the forks being pivotally connected to supports F₁, F₂, and F₃, which in turn, are connected to the free ends of the piston rods of pistons N₁, N₂, and N₃, respectively.

60 Three cylinders M₁, M₂, and M₃ drive pistons N₁, N₂, and N₃ to effect the radial displacement of the rollers B₁, B₂, and B₃, respectively, relative to the workpiece H to insure the continuous contact of the latter rollers with the workpiece as the diameter of the latter varies.

65 Rollers A₁ and A₂ may be either fixed or movable in a radial direction with respect to the workpiece, an apparatus for effecting the latter movement being shown in FIG. 1. Specifically, these rollers are rotatably mounted in forks C₄ and C₅ to rotate about their axes x₁ and x₂, the latter forks being pivotally connected to supports F₄ and F₅ which are connected to the free ends of the piston rods associated with pistons N₄ and N₅ of cylinders M₄ and M₅, respectively.

By virtue of the pivotal mounting of each fork C_1-C_5 with respect to their corresponding supports F_1-F_5 , each roller $A_1-A_2-B_1-B_2-B_3$ can oscillate about its respective axis t_1, t_2, y_1, y_2 and y_3 so that its surface maintains contact with the surface of workpiece H to be straightened, independently of the different tapers and varying diameters of the workpiece within a definite range.

Referring to the specific arrangement of the rollers, the basic straightening device consists of rollers A_1 and A_2 on one side of the workpiece, and roller B_2 on the opposite side thereof and intermediate with respect to rollers B_1 and B_3 .

Rollers B_1 and B_3 are utilized exclusively as drive rollers, i.e., they are driven by external means, not shown, to effect rotary and axial movement of the workpiece in co-operation, of course, with rollers A_1 and A_2 .

Therefore, it is the above-mentioned radial movement of the straightening rollers A_1, A_2 , and B_2 relative to the workpiece which is essential, this movement, of course, being effected by the cylinder-piston devices shown. For example, rollers A_1 and A_2 may be fixed while roller B_2 is movable. Also, roller B_2 may be fixed while rollers A_1 and A_2 are movable, or rollers A_1, A_2 , and B_2 all may be movable.

It is emphasized that this radial movement of any or all of the straightening rollers is such that the rollers are rigidly fixed in their new radial position with respect to the workpiece by means of the hydraulic cylinder-piston means shown, the rollers, of course, being free to pivot about axes t_1, t_2, y_1, y_2 and y_3 .

It is to be understood that the control of the hydraulic cylinder-piston means is effected by automatic means not shown, which senses the variation in the diameter of the workpiece and effects a corresponding change in the hydraulic pressure acting on the respective pistons, during the rotation and translation of the workpiece.

Although the drive rollers B_1 and B_3 are shown as being radially movable by means of a hydraulic cylinder-piston device similar to those used in conjunction with the straightening roller, it is to be understood that these rollers may be mounted in any known manner, such as by elastic means, or the like, since they do not develop any straightening forces on the workpiece.

FIGS. 2 and 3 depict alternate embodiments of the apparatus to effect the radial movement of straightening rollers A_1, A_2 , and B_2 (and drive rollers B_1 and B_3 , if desired), relative to the workpiece H .

In particular, FIG. 2 illustrates the use of a radial cam P which may be rotatably driven about the axis of shaft P_1 by any known means. Cam P acts on the extremity of a bar Q secured to the support F' of a roller B' , and is axially guided by supports Q_1 . Since cam P is eccentric with respect to axis P_1 , rotation of the cam will cause a corresponding movement of the roller B' in a radial direction.

According to another embodiment, a roller B'' may be moved in a radial direction by means of a screw R as shown in FIG. 3. This screw cooperates with a nut screw R_1 secured to support F'' of roller B'' and is guided in an axial direction in support R_2 . The nut screw R_1 is supported by supports S and is adapted to rotate about the axis of screw R by a drive motor (not shown) by means of a helical wheel and worm screw T .

The operation of the apparatus will be described with reference to FIG. 1. The workpiece H is positioned adjacent the path between the rollers A_1, A_2 , and B_1, B_2 , and B_3 and drive rollers B_1 and B_3 are moved into their proper radial position in contact with the workpiece by any known means such as by the hydraulic cylinder-piston as shown, or by elastic means, or the like. Rollers B_1 and B_3 are rotatably driven to rotate and axially move the workpiece between the rollers and the automatic sensing means senses the diameter of the workpiece, and actuates the hydraulic cylinder-pistons, or the like, associated with the straightening rollers A_1, A_2 , and B_2 to

move the latter, or any combination thereof, into engagement with the workpiece.

The rollers A_1, A_2 , and B_2 , due to the rotation of their respective supports about axes G_1, G_2 , and K_2 , assume for each given diameter of the workpiece a suitable inclination to the axis $W-W$ of the workpiece to insure the maximum surface contact, and to apply the forces required to deflect the workpiece with respect to its axis $W-W$ as much as necessary. Due to the rotation and axial movement of the workpiece effected by drive rollers B_1 and B_3 , the workpiece is subjected to said deflection in all directions, thereby causing a straightening of the workpiece throughout its length.

Since the workpieces can have cylindrical lengths and conical lengths with a different taper, the fact that the rollers together with their supports can pivot about axes t_1, t_2, y_1, y_2 and y_3 , insures that the rollers engage the workpiece both in its cylindrical lengths and its conical lengths with different tapers.

Also, the arrangement is such that the angle between the axis of each of said straightening rollers and the axis of the workpiece defined by the projection of said two axes on a plane orthogonal to the line of least distance between said two axes, continuously varies as the outer diameter of the workpiece with which the roller is in contact varies. In other words, a continuous variation of the angle of inclination of the axes of the rollers with respect to the axis of the workpiece in plan view, or looking downwardly from a position over the workpiece and roller, is achieved. This may be effected by allowing the pistons associated with the rollers to freely rotate with respect to their corresponding cylinders, or by freely mounting the supports F on their corresponding piston rods.

This latter movement presents to the workpiece the largest zone of support so as to reduce the specific load and eliminate any possibility of the rollers grooving or marking the workpiece, especially if it is of a tubular thin-walled type.

In the straightening process, the rollers move toward or away from the axis $W-W$ of the workpiece along the axes which intersect centers G_2, K_3 and G_1, K_1 and through the axis of the workpiece (for roller B_2 shifting occurs along an axis which intersects K_2 and which is parallel to the shifting directions of the other rollers). The axes of rotation of the rollers (X and Z) as projected on the plane of FIG. 1 are parallel to the generatrix of the workpiece with which the rollers are in contact at their midsection (i.e. at a point on the line joining centers G_1/K_1 and G_2/K_3).

The axes of rotation of the rollers (X and Z) in their projection according to a plane intersecting the axis of the workpiece, perpendicular to the plane of FIG. 1, are inclined with respect to the axis of the workpiece $W-W$ by angles which are dependent upon the diameter of the tube at the point of contact with the workpiece itself (see FIG. 1A). In particular, for rollers B_1, B_2 and B_3 angle α_1 is greater than α_2 which in turn is greater than α_3 . Similarly, for rollers A_1 and A_2 angle β_1 is greater than angle β_2 .

Provision may be made for imparting a rotation of the respective supports F associated with the rollers about the axis of their corresponding piston rods as shown in FIG. 1, directly in response to the radial movement of the rollers with respect to the workpiece. A device for effecting this is shown in FIG. 4. As shown, the piston rod U of drive piston N''' has a helical projection which cooperates with a helical groove in a sleeve V secured to cylinder M''' .

Thus, with each axial movement of rod U , a rotation of the rod about its own axis takes place and therefore, a variation of the angle of inclination of the axis of roller B with respect to the axis of the workpiece, in a plan view is achieved, as a direct function of the radial distance of the roller from the axis of the workpiece, which

of course, is a function of the diameter of the workpiece at its contact point with the roller.

In known machines on which workpieces having a constant diameter are straightened, the drive rollers may be rotated with the same number of revolutions. However, in the present invention, since drive rollers B_1 and B_3 may, at any given time, be in engagement with diameters of a varying size, such as in the case when one of the drive rollers engages a cylindrical portion of the workpiece and the other, a conical portion, number of revolutions which said drive rollers must rotate to avoid sliding on the workpiece, must be adjusted continuously. This may be achieved by means of a kinematic differential mechanism inserted on the drive of the two driving rollers, if the latter are operated by a single motor or by means of an electrical differential, if operated by separate motors.

In this manner, the correct kinematic condition of entrainment or rollers B_1 and B_3 in engagement with such a workpiece is insured, and therefore, a suitable helicoidal motion will be imparted to the workpiece.

Of course, other variations of the specific construction and arrangement of this type device herein disclosed can be made by those skilled in the art without departing from the invention as defined in the appended claims.

I claim:

1. A device for straightening conical, tapered or stepped workpieces, comprising a plurality of straightening rollers engaging the periphery of a workpiece at approximately opposite sides thereof, means to rotate and axially translate said workpiece along a path between said straightening rollers to straighten said workpiece, and means unresiliently mounting at least one of said straightening rollers for individual driven movement in a radial direction with respect to said workpiece in response to variations in the diameter of the workpiece during movement thereof, said mounting means including means

whereby said radial movement is combined with a driven rotation of said rollers about the axes of their respective mounting means to vary the angle of inclination of said rollers with respect to the workpiece.

5 2. A device as set forth in claim 1 further comprising additional means mounting said straightening rollers for a free pivotal movement about an axis perpendicular both to the axis of the roller and to the axis of the respective mounting means.

10 3. A device as set forth in claim 1 wherein said means to rotate and axially translate said workpiece comprises at least one drive roller adapted to engage said workpiece.

4. A device as set forth in claim 1 wherein said mounting means comprises a hydraulic system.

15 5. A device as set forth in claim 1 wherein said mounting means comprises a cam arrangement.

6. A device as set forth in claim 1 wherein said mounting means comprises a screw-nut assembly.

20 7. A device as set forth in claim 1 wherein each of said rollers has a concave profile.
